E. SAUTREAU

DEVICE FOR FASTENING AND LEVELING RAILWAY RAILS

Filed Aug. 23, 1924

Fig. 2.

Fig. 4.

Inventor:

Eugene Sautreau

UNITED STATES PATENT OFFICE.

EUGÈNE SAUTREAU, OF NANCY, FRANCE.

DEVICE FOR FASTENING AND LEVELING RAILWAY RAILS.

Application filed August 23, 1924. Serial No. 733,821.

To all whom it may concern:

Be it known that I, EUGÈNE SAUTREAU, a citizen of the French Republic, residing at Nancy, France, have invented certain improvements in a Device for Fastening and Leveling Railway Rails, of which the following is a specification.

This invention relates to a device for fastening and leveling railway rails of the Vignoles type, and consists in the combination with a chair having jaws between which the rail can be supported in a more or less elevated position, of hard-wood wedges arranged on the sleeper at opposite sides of the chair so as to support the rail, the jaws being recessed and drilled to accommodate clamps and screws whereby the rail is clamped to the supporting wedges.

Fig. 1 of the accompanying drawings represents a perspective view of the chair, partly in section, and

Fig. 2, a perspective view of one of the clamps.

Fig. 3 is a perspective view of a set of rail supporting wedges, and

Fig. 4, a perspective view showing the device in use.

The chair 1 is provided with jaws 3 between which the rail is vertically adjustable so that it can be supported in different altitudes within the chair. The vertical thrust of the rail is taken by wedges of hard-wood arranged on the sleeper at opposite sides of the chair. The taper of these wedges is chosen so that the rail will be maintained by the latter at the proper, customary inclination towards the centre of the track. By a longitudinal adjustment of the wedges, the rail can be raised and lowered in the chair for leveling the track. To allow a large scope of adjustment without employing excessively long wedges, it is preferable to use sets of short wedges, such as 6, 9 and 10 (Fig. 3), which differ as regards thickness and act as continuations of each other. The thinnest wedge is thicker than the sole plate 4 of the chair so that it can hold the rail clear of said sole plate.

The rail is clamped to the wedges by means of clamping pieces 5 which are accommodated in recesses made in the jaws 3 and which are held by screws driven through the chair into the sleeper. The clamping pieces are arched so that the thrust will always be taken by the outer

end 8 thereof whatever be the elevation of the rail within the chair. The screw aperture 7 in the clamping piece is flared and elongated so as to allow the angular position of the clamping piece to be altered without resistance on the part of the screw. The clamping piece is provided with a tall head so that it can be easily reached from between the webs of the jaw.

The holes for the clamping screws are situated in the centre line of the jaws. Additional screw holes at the outer ends of the chair are arranged at opposite sides of the centre line. The wedges are fastened by spikes driven into the sleeper, washers being employed to prevent the spike heads from entering the wood. This arrangement allows the spikes to be easily extracted when a readjustment of the wedge is necessary.

In laying the track, the rails are clamped to the wedges, and the latter are secured by means of the spikes. After the track has been rammed in the usual manner, leveling can take place by loosening the fastenings and readjusting the wedges. Any deviation from the true level can thus be easily corrected.

The improved arrangement imparts considerable firmness to the track. The sleepers are protected from wear. The only elements subjected to vertical concentrated stress are the wedges, and as these are made of inexpensive material and can be easily renewed, the track can be kept in repairs at a small cost.

The construction of the chair may be varied without departing from the spirit of the invention. If metal or concrete cross-ties are used, the fastening may be effected by means of bolts and anchors. Grooves may be made in these ties to form guides for the wedges.

I claim:

1. A device for fastening and leveling railway rails of the Vignoles type, comprising a chair having jaws between which the rail is supported in an elevated position, wedges of hard-wood arranged at opposite sides of the chair as supports for the rail, and means for clamping the rail to the wedges.

2. A device for fastening railway rails of the Vignole type to the sleepers and for leveling the same, comprising a chair hav-

ing recessed jaws between which the rail is supported in an elevated position, wedges of hard-wood arranged on the sleeper at opposite sides of the chair as supports for the rail, clamps accommodated in the recesses of said jaws, so as to bear against the chair and against the rail foot, and clamp screws passed through the clamps and through the chair into the sleeper for fastening the elements in position.

3. A device for fastening railway rails of the Vignoles type to the sleepers and for leveling the same, comprising a chair having recessed jaws between which the rail

is supported in an elevated position, wedges of hard-wood arranged on the sleeper at opposite sides of the chair as supports for the rail, arched clamping members accommodated in the recesses of said jaws so as to bear with one extreme end against the chair and with the other end against the foot of the rail, and clamp screws passed through the clamping members and through the chair into the sleeper for fastening the elements in position.

In testimony whereof I have signed my name to this specification.

EUGÈNE SAUTREAU.
